Peter Peterson

UNITED STATES PATENT OFFICE.

PETER PETERSON, OF MINNEAPOLIS, MINNESOTA.

TOY CANNON.

1,414,827.

Specification of Letters Patent.

Patented May 2, 1922.

Application filed January 6, 1921. Serial No. 435,390.

To all whom it may concern:

Be it known that I, PETER PETERSON, a subject of Norway, residing at Minneapolis, in the county of Hennepin and State of Minnesota, have invented certain new and useful Improvements in a Toy Cannon, of which the following is a specification.

This invention relates to toys and more particularly to improvements in toy fire 10 arms.

The primary object of the invention is to provide a toy cannon operated by a spring and adapted to be released by a trigger whereby small balls or wads of paper may be 15 discharged from the cannon to afford amusement for children.

Other objects of the invention will appear upon consideration of the following detail description and accompanying drawings, wherein:—

Figure 1 is a longitudinal section through the cannon constructed in accordance with my invention.

Figure 2 is a transverse section through 25 the same.

Referring to the drawing by numerals, the base 1 may be of any form large enough to conveniently support the cannon and the base is adapted to receive a pivot pin 2 rotatably mounted so that the cannon may turn 30 in any desired direction. A U-shaped bracket 3 is mounted upon the swivel pin 2 and the opposite ends of the bracket embrace the barrel 4 of the cannon. The latter is of cylindrical tapered formation and has a hollow bore 5 within which a metallic sleeve 6 is mounted to form a lining for the bore whereby the piston or plunger 7 may freely move longitudinally within the 35 bore. A longitudinal slot 8 is provided in the barrel of the cannon and a guide arm 9 is secured to the plunger 7 and extends upwardly through the slot where it is attached to a guide rod 10 longitudinally movable through eyelets or guide members 11 and 12. A brace ring 12' embraces the barrel of the cannon and trunnions extend outwardly from opposite sides thereof where they are pivotally engaged with the opposite 40 ends of the bracket 3 as shown in Fig. 2 so that the barrel of the cannon is pivotally mounted.

Extending longitudinally through the interior of the bore and connected to the plunger 7 is a connecting rod or plunger rod 13. A collar 14 is secured to the large end of

the cannon and the plunger rod 13 is slidably mounted through the collar and is provided with a finger ring 15 whereby the plunger rod may be manually withdrawn through 60 the collar to retract the plunger 7. A coil spring 16 is interposed between the collar 14 and the plunger.

The guide rod 10 is provided at its inner end with a lip 17 adapted to be engaged 65 by the hook end 18 of a trigger member 19 which is pivotally mounted on a bracket 20. The trigger member is provided with a finger piece 21 adjacent the ring 15 whereby the operator may press the trigger to release the 70 hook end 18 for the purpose of releasing the member 17 whereby the guide rod will slide forwardly when released to permit the spring 16 to force the plunger outwardly whereby the projectile will be emitted from 75 the mouth of the cannon. A flat spring 22 is employed to maintain a tension on the trigger in the proper manner.

Minor changes may be made in the details of construction without departing from the 80 spirit of the invention or the scope of the claims hereunto appended.

What is claimed is:—

1. A toy cannon comprising a pivotally mounted barrel having a central bore, a 85 sleeve lining within the bore, the said barrel also having a longitudinal slot communicating with the said bore, a plunger element having a guide arm attached thereto and extending upwardly through the slot, a guide rod above the said barrel and connected with the said guide arm, the said guide rod being mounted for longitudinal sliding movement, a plunger rod connected to the said plunger within the bore and extending longitudinally through the same, a collar at one end of the barrel having the said plunger rod slidably extended therethrough, a coil spring interposed between the plunger and the said collar to normally force the said plunger 90 outwardly, a trigger member pivotally mounted in one end of the barrel and having a hook end adapted to engage one end of the said guide rod when the said spring is withdrawn whereby the spring may forcibly 95 eject the plunger through the bore when the said guide rod is released by operation of the said trigger.

2. A toy cannon comprising a barrel having a central bore, a sleeve within the bore, a longitudinal slot through the barrel and sleeve communicating with said bore, a plun-

ger slidably mounted in the sleeve, a collar covering one end of the bore, a plunger rod connected with the said plunger and passing through said collar for retracting the plunger, a coil spring interposed between the plunger and said collar to normally force the plunger outwardly, a brace ring surrounding the barrel midway its length, an eyelet 5 projecting from the ring in alinement with said slot, a second eyelet mounted on the open end of the barrel in alinement with the first mentioned eyelet, a guide rod having a hook end slidably mounted in said eyelets, an arm extending through said slot connect-

ing the guide arm with the plunger to limit 15 the movement of the latter, and a trigger member pivotally mounted on the barrel engageable with the hook end of said guide rod to hold the plunger in a retracted position whereby the spring is compressed so it 20 may forcibly eject the plunger when the trigger is released.

In testimony whereof, I have affixed my signature in the presence of two witnesses.

PETER PETERSON.

Witnesses:

ELMER E. JEFFERSON,
FRANCES JEFFERSON.
